DEVICE FOR DECANTING A LIQUID FROM
HOLLOW OBJECTS

Hendrik Lems, Eindhoven, Netherlands, assignor, by
mesne assignments, to North American Philips Company, Inc., New York, N.Y., a corporation of Delaware

Application June 21, 1956, Serial No. 592,814

3 Claims. (Cl. 214—318)

This invention relates to devices for decanting a liquid from hollow objects, in which during decanting a covering layer is applied to a wall of the object or a covering layer which already exists on this wall is not affected.

It is of frequent occurrence that an object must be provided with an inner covering layer. For this purpose the hollow object has introduced into it a liquid, which serves as a carrier for the chemicals for producing the covering layer. These chemicals may be contained in the liquid, for example, as an emulsion or may be dissolved therein or may float as a layer on the liquid. The liquid and any excess chemicals must be removed from the hollow object, which is usually effected by decanting. The decanting process must take place very carefully, since during decanting either the desired covering layer is applied to the wall of the object, or an existing covering layer, which has been formed, for example, by settling down, must not be disturbed.

The abovementioned problem may occur, for example, in applying silver mirrors to Dewar vessels, in which the wall is provided with a thin covering layer before applying the metallic layer.

In electric discharge tubes also it may be desirable for the wall to be provided with a certain covering layer. Thus, in iconoscopes, a layer of small oxidized silver balls is frequently covered with a film of foil before the metallic layer is provided.

By way of example, reference may also be made to the internal coating of an object with a luminescent screen. The grains of luminescent material are frequently brought into a liquid solution contained in the object and settle down therein so as to form a covering layer on the wall of the object, for example, a cathode-ray tube. Subsequently, the liquid is decanted, during which process the layer formed must not be disturbed.

The luminescent layer is frequently covered with a layer of organic material e.g. a nitrocellulose solution. For this purpose the cathode-ray tube is filled with liquid, for example water, whereafter a certain amount of a nitrocellulose solution is poured onto the water, which layer floats on the water. When the liquid is decanted, the nitrocellulose solution lays itself as a covering layer on the luminescent grains, while the water and the excess nitrocellulose solution is decanted.

It is also possible to provide a film on the water level, which film lays itself as a foil on the luminescent layer after the water has been decanted. Said film may be obtained, for example, if a drop of zapon lacquer is poured onto the water level.

It is absolutely necessary during decanting to ensure that the machine is substantially not subject to vibrations.

The decanting process might be effected by placing the objects on an endless belt, the extremity of which runs over a roller and of which the parts moving forwards and backwards are located over one another. When the roller is passed, the objects are tipped. This method has the disadvantage that the installation is voluminous and difficult to make free from vibration. Besides, the tilting

movement in this device is a uniform rotation and this is frequently undesirable.

The object of the invention is to mitigate the above-mentioned disadvantages.

5 The device according to the invention is characterized in that it comprises a turret, which can rotate about a vertical shaft and which possesses means for securing the hollow objects, which means are pivotally arranged with respect to the turret, so that each means, together with 10 the hollow object secured thereto, can be tilted, resulting in liquid being decanted from the hollow object, the device also comprising control means which co-operate with the means for securing the objects in such manner that, during rotation of the turret, said means are tilted at a given position.

The devices for securing the hollow objects may be realised in different ways. It is possible, for example, to provide this device with clamps holding the object in position. In one advantageous embodiment of the invention, each of the means for securing the hollow objects comprises a table having a cavity, to which a vacuum line is connected, while at least the edge of the cavity is provided with resilient material. The resilient material may be, for example, rubber.

15 20 25 30 If each of the means for securing the hollow objects comprises a holder, then according to another advantageous embodiment of the invention, each holder may be secured to the turret by means of two lugs and tilt outwardly.

The control means may be realised in different ways. It is possible, for example, to move the means for securing the objects with the aid of oil pressure or air pressure. In one advantageous embodiment of the invention, the control means comprise a rail surrounding the frame of 35 the turret, each of the means for securing the hollow objects having a roller co-operating with the rail. This construction affords the advantage that another program for the machine is obtained by replacing the rail by another.

40 45 In another embodiment of the invention, it is desirable for this construction that the centre of gravity of the holder and the object placed thereon should be located such that the holder has a tendency to tilt outwards. Due to this construction, the holder always pushes against the rail, so that the path of the rail is followed accurately.

In another embodiment of the invention, each holder also possesses a second roller, the two rollers being located on each side of the rail and one roller being pushed against the rail due to the weight of the holder and the object placed thereon, whereas the other roller is pulled against the rail by means of a spring, so that an additional guarantee exists that the path of the rail is followed accurately.

In another embodiment of the invention, the rail may 50 55 be realized in a simple manner and preferably comprises a circular rod, of which not only the upper side, but during the tilting of the holders also the side may be utilized as a running surface. It has been found that it is frequently advantageous that the tilting movement is no uniform rotation. Such may especially be the case, if during the decanting of liquid a covering layer is applied to the wall. In one embodiment of the invention, the angular speed of the tilting movement is varied during

60 65 70 decanting. In another embodiment, the angular speed of the tilting movement during the last portion thereof is greater than during the first portion of this movement. If a covering layer is to be applied to the wall, the tilting movement especially during the first portion thereof preferably takes place very regularly and slowly. In one embodiment of the invention, the control means for tilting the objects are so shaped that the angular displace-

ment is at most 20° per minute during the first portion of the tilting movement.

The first portion of the tilting movement may last from about 2 to 3 minutes, the covering layer during this period laying itself against the upper side of the wall. It is now desirable that the movement is accelerated (allowance having to be made for the viscosity of the covering layer) so that it may be achieved that the layer acquires a uniform thickness. During this period, an angular displacement of even 60° per minute may occur. At the end of this period, the object is tilted to such an extent that the liquid is decanted from it.

In order that the invention may be readily carried into effect, it will now be described, by way of example, with reference to the accompanying drawings, in which:

Fig. 1 is a diagrammatic perspective view of a device according to the invention;

Fig. 2 is a perspective view on an enlarged scale of a table, on which a hollow object may be placed;

Fig. 3 shows an example of the curve, after which the tilting movement of the hollow object may take place.

The device shown in Figs. 1 and 2 comprises a turret 1, which is secured to a frame (not shown) and which can rotate in a horizontal plane about a vertical shaft 2. Supports 3 have lugs 4 arranged on this turret at different areas. Rotatably arranged between the lugs 4 are holders 5, each having a cavity 6 with resilient material 7 at the edge and an aperture 8 for a vacuum connection, which aperture is connected via a line 9 to a central vacuum line. The holders 5 each have two guide rollers, viz. an upper roller 10 and a lower roller 11. The upper roller 10 is rigidly secured to the holder, whereas the lower roller 11 can rotate at point 12 and is pulled upwards by means of a spring 13.

The frame is surrounded by a rail 14, which co-operates with the rollers 10 and 11 of the holders 5 and which controls the tilting movement of the holders during the rotation of the turret. Since the centres of gravity of the holders 5 are located externally, the rollers 10 always urge against the upper side of the rail, therein supported by the tension of the springs 13, which pull the lower rollers 11 upwards. Each holder also has a discharge trough 15 for any liquid which may reach the holder. A plurality of hollow objects, for example cathode-ray tubes 16, of which only a few are shown, are placed on the holders. The rail 14 near the portion 17 is so shaped that the holders tilt at this area.

The device operates as follows: The hollow objects, for example, cathode-ray tubes, which are filled, for example, with water, are placed on the holders, a layer of nitrocellulose solution, for example, floating on the water level. The objects are pushed against the holders as a result of the subpressure prevailing in the cavities 6 of the holders 5. The turret rotates about the shaft 2, so that the holders, together with the cathode-ray tubes, tilt near the portion 17 of the rail.

During the first portion of the movement the tilting movement takes place substantially uniformly with a small angular displacement, until the layer of the nitrocellulose solution has partly laid itself against the screen of the cathode-ray tube. Subsequently, the angular displacement is increased, so that finally the liquid is decanted from the cathode-ray tube and may be collected in a container 18. Subsequently, the holder tilts back, whereafter the cathode-ray tube may be removed by local suppression of the vacuum of the holder.

Figure 3 shows, by way of example, a decanting curve, in which the angular displacement of the holder and the time are plotted on the vertical axis and the horizontal axis, respectively.

This curve shows that during the first minutes the object tilts with a substantially constant angular speed, which is small and less than 20° per minute, whereafter

the angular displacement increases to a considerable extent and may be even more than 60° per minute.

The device according to the invention, in addition to being simple of construction and little subject to vibration, has the advantage that different processes may be carried out on the turret. For this purpose commands may be given in a simple and known manner.

If the device is used for providing a luminescent screen in television tubes, then at one stage of the turret the tubes may be filled with a liquid in which luminescent material is suspended. During some stages, this luminescent material may settle down so as to form a covering layer on the base of the tube.

At a subsequent stage, the liquid may be acidified, whereafter a nitrocellulose solution is poured onto the liquid. Finally, the liquid may be decanted, during which process the nitrocellulose layer lays itself on the luminescent layer. As an alternative, it is possible that, at one stage of the decanting process, while the tube still has its aperture directed downwards, water is sprayed into the tube to remove any available covering layer on parts of the wall, where this layer is not wanted.

If a different program is desired for the tilting movement, the rail 14 may be replaced by another rail. The portion 17 of the rail 14 is bent downwards and inwards to permit the tilting of the holders 5. During tilting, the rollers 10 and 11 no longer run along the upper side of the rail 14, but along the side thereof.

What is claimed is:

1. A device for decanting liquid from container-like objects initially in a substantially vertical position comprising a rotatable turret, a plurality of holders for said objects each having a recess and resilient material lining at least on the edge of said recess, each of said holders being provided with a funnel-shaped trough having an opening, a vacuum line connected to said recess, each of said container-like objects being located in a recess and held therein by the subpressure created therein means pivotally mounting said holders on said turret for tilting said objects at predetermined locations whereby any liquid on said holders is discharged through the opening in each of said funnel-shaped troughs, a receptacle for collecting said decanted liquid, and control means on said device which during rotation of said turret controls the location and tilting rate of said holders.

2. A device for decanting liquid from container-like objects initially in a substantially vertical position comprising a rotatable turret, a plurality of holders for said objects, means pivotally mounting said holders on said turret for tilting said objects more than 90° at predetermined locations, a receptacle for collecting said decanted liquid, control means on said device which during rotation of said turret controls the location and tilting rate of said holders, said control means including a rail having a portion bent downwardly and inwardly and surrounding said turret, and each holder being provided with two rollers located at opposite sides of said rail and co-acting therewith, one of said rollers being spring-urged into engagement with said rail.

3. A device for decanting liquid from container-like objects initially in a substantially vertical position comprising a rotatable turret, a plurality of holders for said objects, means pivotally mounting said holders on said turret for tilting said objects more than 90° at predetermined locations, a receptacle for collecting said decanted liquid, control means on said device which during rotation of said turret controls the location and tilting rate of said holders, said control means including a rail having a portion bent downwardly and inwardly and surrounding said turret, and each holder being provided with at least one roller bearing against the top surface of said rail and that during the first portion of said tilting movement the angular displacement of said holder is at most 20° per minute.
